SCREEN FOR RECEIVING PROJECTED IMAGES

Francis Earle, Montclair, N. J., assignor to The Mearl Corporation, Montclair, N. J., a corporation of New Jersey

Application March 9, 1933, Serial No. 660,115

8 Claims. (Cl. 88—24)

This invention relates to screens for receiving projected images.

The invention provides screens, admirably suited for use in the motion picture, television and allied arts, which impart improved quality and depth to the projected images, eliminate distortion of the images when viewed from an angle, reduce specular reflection to a minimum and in many other respects give greatly improved results over those obtained when any of the various conventional screens are employed.

Further, the screens contemplated by the present invention impart a highly desirable stereoscopic effect to the images projected thereupon. Among numerous other advantages and novel features, the present invention provides screens which greatly reduce eye strain in the auditors.

The present invention provides screens for receiving projected images in which a special coating or receiving medium is utilized capable of both reflecting and refracting the light.

The particular receiving medium or coating that I have discovered gives desirable and totally unexpected results is composed wholly or in part of pearl essence either natural or artificial. No special grade of pearl essence is required but certain modes of procedure in applying it may be desirable as hereinafter noted.

The screens to which my improved coating may be applied may be of standard construction such as solid texture or perforated. While white, black or aluminum backgrounds are preferred, excellent results have been secured even when colored backgrounds have been employed. However, with colored backgrounds or surfaces, there is a tendency for the light reflected to the observer to partially exhibit that color and thus lose some of its chiaroscopic nature. Again, the background may be chosen from a host of materials among which may be mentioned leather, paper, glass, textiles, metals, wood, etc.

While I prefer using a nitrocellulose lacquer as a vehicle for the pearl essence in applying same to any particular background, it is obvious that many other carriers may be utilized, some of the more common being cellulose acetate, ethyl cellulose, synthetic resins, gelatine and various varnishes. Instead of spraying, the pearl essence may be applied to the desired background in other manners, such as by brushing, dipping, spreading, etc.

The following specific example will serve to illustrate one method of manufacturing the improved screens of the present invention. In this

instance, white imitation leather, that is cotton material coated with pyroxylin carrying a white pigment, was utilized as a background. Pearl essence was then incorporated in lacquer and the resulting mixture applied to the background. This coating action was accomplished by means of an ordinary spray gun and upon drying the screen was suitable for use.

It is, of course, understood that the above example is given merely as an illustration and is not to be construed in any sense as a limitation of the broad scope of the invention. Obviously, any other methods of manufacturing screens of the type described may be practised, while, at the same time, the invention may be adapted to a great variety of screens suitable for receiving projected images.

Various other modifications of the invention will be readily apparent to those skilled in the art. For example, lacquer containing essence of pearl may be poured into a suitable tray, allowed to dry, the resulting film stripped therefrom and utilized as a screen itself or cemented or otherwise applied to a desired background. Again, pearl essence lacquer may be allowed to flow into a moving drum, the sheet stripped and utilized as a screen. A screen having the desired properties may also be formed from cloth in which the pearl essence is incorporated, as, for example, by extruding fibres through which pearl essence is disbursed and weaving a suitable screen therefrom. As already mentioned, either natural pearl essence or the synthetic imitations of the same, such as the so-called H-scale and the like, may be utilized in producing screens for receiving projected images in accordance with the principles of the present invention.

Many new, improved and beneficial results are obtained by projecting images upon screens coated with pearl essence or screens impregnated with that material. The screens are characterized by their ability to clearly define and reflect images, while, at the same time, diffusing the reflected light in all angular directions thus giving a maximum of reflectibility with a minimum of glare and allowing the images to be viewed from sharp angles without distortion or eye strain to the auditor. While a maximum of reflected light is obtained by utilizing screens coated or impregnated with pearl essence so that images may even be viewed in broad daylight, the diffusion of the reflected light is so nearly perfect that halos and specular reflections are reduced to an absolute minimum or entirely eliminated. In addition, a pronounced stereoscopic effect is produced thus

giving the projected images the desired illusion of depth.

Screens possessing these desired properties may be readily and economically produced in any desired shape or size. In addition to the novel and beneficial characteristics already described, such screens are washable and non-tarnishable and may thus be readily cleaned, a feat often impossible with many of the standard screens heretofore used in the projection of images.

It is believed that the beneficial results attending the use of the improved screen in receiving projected images may be traced, in part at least, to the microscopic and characteristic crystalline structure of pearl essence particles. However, this is advanced merely as an hypothesis, as it is possible that other properties peculiar to pearl essence, not known to the applicant, explain the advance in the art.

While certain novel features of the invention have been disclosed and are pointed out in the annexed claims, it will be understood that various omissions, substitutions and changes may be made by those skilled in the art without departing from the spirit of the invention.

What is claimed is:

1. A screen for receiving projected images comprising a background and a lacquer surface coating with crystals of pearl essence dispersed therein.
2. An improved screen for receiving projected images comprising a lacquer-like substance containing pearl essence.
3. A screen for receiving projected images which effects a maximum reflection without

specular reflection and in which pearl essence in combination with a lacquer base is a basic constituent.

4. A process for manufacturing a screen suitable for use in projecting motion picture images containing pearl essence as a necessary constituent which comprises forming a mixture of pearl essence and lacquer and uniformly spraying said mixture on a suitable background whereby a screen capable of diffusing light with a maximum of reflection and a minimum of glare is produced.

5. A washable screen capable of diffusing and reflecting projected rays in such manner that specular reflections are reduced to a minimum which comprises in combination an opaque background and a lacquer coating layer containing pearl essence.

6. The improvement in projecting desired images to render same visible to observers which comprises projecting said images upon a textile fabric impregnated with crystals of pearl essence carried in a lacquer base.

7. A screen for receiving and reflecting projected images comprising a backing member of white imitation leather having a coating thereon of lacquer carrying particles of pearl essence in suspension.

8. A screen for receiving and reflecting television images which are of relatively low intensity which comprises a backing sheet of white imitation leather coated with a lacquer, and particles of pearl essence mixed with said lacquer.
